ALFRED MEHLHORN, OF DIETRICHSDORF, NEAR KIEL, GERMANY.

STEAM-ACTUATED VALVE.

No. 914,152.

Specification of Letters Patent.

Patented March 2, 1909.

Application filed October 5, 1906. Serial No. 337,550.

To all whom it may concern:

Be it known that I, ALFRED MEHLHORN, a subject of the King of Prussia, and resident of Dietrichsdorf, near Kiel, in the Kingdom 5 of Prussia and German Empire, have invented new and useful Improvements in Steam-Actuated Valves, of which the following is a specification.

My present invention relates to improvements in valve gears for direct acting steam pumps, of the kind in which at each end of the pump piston stroke a piston valve is shifted by moving parts of the pump until a steam inlet port is opened, whereupon the 10 piston valve is moved to the end of its stroke by steam pressure alone. An existing device of this kind has the drawback that the valve piston is kept in a balanced condition by live steam acting at both ends during the 15 whole stroke of the pump, which, on the one hand, entails a great waste of steam and, on the other hand, causes the piston valve to be easily displaced by external influences. In addition to this the piston valve so balanced 20 can only be disposed horizontally, as in the vertical position the weight thereof would disturb the action.

According to my present invention, the piston valve of such a pump is loaded by 25 steam at one or the other of the two ends throughout the entire stroke of the pump, and only unloaded toward the end of such stroke by a mechanically moved auxiliary or slide-valve connecting the steam loaded 30 end of said piston valve with the exhaust.

In addition to overcoming the above drawbacks the new construction has the further advantage that the expansion of the steam, which had been compressed at one end of the 35 piston valve before the balanced condition was brought about at the other end of said piston, assists the mechanical or direct operation of the piston valve while it is passing from the loaded into the unloaded or balanced condition. The mechanical or direct operation of the piston valve is preferably obtained by providing inclined tappets on the slide valve, which for its part is operated by the pump with the assistance of 45 suitable tappets. Said inclined tappets are given a certain amount of play in regard to suitable tappets or stops provided on the piston valve, in order to prevent said valve from being mechanically operated until it has 50 been unloaded or balanced in the manner described.

In the accompanying drawing my invention is illustrated by way of example.

Figure 1 is a longitudinal section of the piston valve, showing the manner in which it is mechanically operated by the slide valve. 60 Fig. 2 shows a section on the line A—B in Fig. 1. Fig. 3 is an elevation of the pump cylinder and valve box showing how the slide valve is operated by the piston through the agency of 65 tappets.

Referring to Fig. 3, *a* is the pump piston rod, which carries a fixed sleeve *b*, to which one end of a lever *e*, provided in known manner, with a telescopically sliding part, is pivoted, the other end of said lever being adapted to operate the valve rod *a'* by being turned up and down about its fulcrum and striking against the stops *c*, *d*. 70

In order to unload the piston valve *o*, the 75 slide valve *f* (Fig. 1), to which the valve rod *a'* is fastened, when commencing to move by reason of the main piston of the pump approaching the end of its stroke, connects the channel *g* with the exhaust port *h*, by which 80 means the space between the end of the cylinder and the piston valve end *m*, of which during the whole previous stroke on the pump, live steam had acted through the channel *g*, is exhausted. At the same time 85 the steam compressed in the cylinder by the end *l* of the piston valve *o* expands, until the pressure at both ends *m* and *l* is the same. When the piston valve *o* has been thus unloaded through the agency of the 90 slide valve *f*, the tappet on the latter bears against the piston valve, until the end *l* opens the channel *i*, it being immaterial whether this channel *i* is opened simultaneously by both the slide valve and piston, or 95 firstly by the slide valve and then by the piston. As soon as the channel *i* has been opened by the piston valve end *l* the latter is exposed to live steam and is accordingly moved thereby, and, in this way, the pump 100 is reversed. Thereafter the valve piston end *m* closes the channel *g*, and the steam is then compressed at that end of the piston, thus preventing the piston from striking against the cover plate of the cylinder. 105 These operations are repeated in the opposite direction as soon as the piston of the pump arrives at the opposite end of its stroke.

In the construction shown in the drawing 110 the slide valve operates the piston valve by means of inclined tappets *p*, *p'* provided

on said slides, which strike against suitably shaped stops q, q' on the piston valve. Between the tappets on the slide valve and the stops on the piston valve sufficient space is provided, to enable the piston valve, after it has been mechanically moved for a certain distance, to complete its stroke under the influence of the steam, without striking against said slide valve, and also to enable the above mentioned unloading or balancing of the piston valve to be brought about before the mechanical movement of the same by the slide valve commences.

It is immaterial whether the piston valve controls the distributing valves of one or several steam cylinders.

In Fig. 1 r and r' are the steam inlet ports for the ends of a single steam cylinder, and s, s' are the outlet ports by which the steam from said cylinder is conducted to the spaces t, t' of the piston valve, in order to be conducted to the exhaust.

What I claim and desire to secure by Letters Patent is:—

1. In combination with a steam cylinder and working piston a steam actuated valve, comprising in combination, a piston valve, a cylinder containing said piston valve, a steam chest in said cylinder, two channels connecting said steam chest with said cylinder near to each end respectively, an auxiliary valve body adapted to open one of said channels to the exhaust before the other

channel is opened to live steam, and tappets on said auxiliary valve body adapted to mechanically move said piston valve when the one of said channels has been opened to the exhaust and before the other of said channels is opened to live steam, substantially as, and for the purpose set forth. 40

2. Valve mechanism for direct acting steam pumps, comprising in combination, a piston valve to control the steam passages of the steam cylinder, a cylinder containing said piston valve, a steam chest in said cylinder, two channels connecting said steam chest with said cylinder near to the opposite ends respectively, an auxiliary valve body adapted to be moved transverse to the direction of motion of the piston valve so as 50 to open one of said channels to the exhaust before the other channel is opened to live steam, and tappets on said auxiliary valve body adapted to mechanically move said piston valve when one of said channels has 55 been opened to the exhaust and before the other of said channels is opened to live steam, substantially as, and for the purpose set forth.

In testimony whereof I have hereunto set 60 my hand in the presence of two subscribing witnesses.

ALFRED MEHLHORN.
